UNITED STATES PATENT OFFICE

JOSEPH F. MORAN, OF WATERBURY, CONNECTICUT, ASSIGNOR TO SCOVILL MANUFACTURING COMPANY, OF WATERBURY, CONNECTICUT, A CORPORATION OF CONNECTICUT

METAL BOX

Application filed March 18, 1930. Serial No. 436,677.

This invention relates to certain improvements in metal boxes of that type including a body and a cover which are secured together by a catch.

5 Small metal boxes have now come widely into use for holding cosmetics, cigarettes or the like. These boxes are carried in the purse or pocket of a user, and to be practical must be very light, and it is desirable that the meeting edges of the box when closed be very thin, these boxes being commonly known as of the knife-edge type. As the metal of these boxes is light and where the box is a thin edge box there is very little space at the edge, 10 difficulty has been experienced in producing a catch construction which will hold these boxes closed and which can be operated in this small space, and which will be sufficiently strong to withstand the constant use to which 15 such boxes are given, and furthermore as these boxes have heretofore been constructed the catch required considerable space to operate.

It is the especial object of the present invention to produce an improved catch construction particularly adapted for thin-edge boxes which will take up little room so that it can be used with boxes having very thin edges.

20 A further object of the invention is to produce a very thin flat metal box of attractive appearance and of few parts so that it can be easily and economically produced and assembled.

25 With these and other objects not specifically referred to in view, the invention consists in certain novel parts, arrangements and combinations which will be described in connection with the accompanying drawing and the novel features pointed out in the claims hereunto annexed.

In the drawing,—

Figure 1 is a top view of the box embodying the invention, the parts being shown 30 closed;

Figure 2 is a view of the box shown in Figure 1, the parts being shown open;

Figure 3 is a vertical sectional view taken on the line 3—3 of Figure 1 and on a somewhat larger scale, and

50 Figure 4 is a detail sectional view, partly broken away, taken on the line 4—4 of Figure 2.

Referring now to this drawing, the box selected to illustrate the invention is a two part metal box embodying a body and a cover which meet in a thin edge, and the box shown is capacitated to hold cigarettes. It will be understood, however, that the invention is applicable to other objects of different shapes and capacitated to hold other articles, such as cosmetics. The box shown, however, includes a body 1 and a cover 2, made of light thin metal and so arranged that when closed the edges of the box meet in a thin edge, as 55 indicated at 3, so as to produce a very flat container. These parts are associated on a hinge conveniently formed by bending over parts of the metal of the cover and body to form hinge-knuckles 4, which are united by a 60 pintle 5, and if desired this pintle may be provided with a spring 6 so that the box will 65 open quickly and readily.

70 In accordance with the invention, there is provided a catch device of improved construction which takes up little space in the box and which may be manipulated in a very small space so that it may be used with the thin-edge boxes in which operating space for a catch is very limited. While this catch 75 mechanism may be of various constructions, it will include a catch member of resilient metal, which is so arranged that the pressure on the member to open the box is through its wide instead of its narrow dimension, that is, 80 the member is so arranged that its wide dimension is horizontal with the plane of the box instead of vertical, as in the usual constructions. This permits a very narrow 85 spring member to be used to give the required 90

resiliency and play, and at the same time requires but a slight play of the parts to release the catch when the box is closed.

While this spring member may be of various constructions, in the best form such member will also have formed integrally therewith the thumb-piece by which it is operated. In the particular construction shown the body of the box has secured therein a spring 10 strip catch, which is clearly shown in Figure 2, arranged flatwise so that the pressure is through the wide dimension of the member. This spring catch has secured thereto, preferably integrally, a finger-piece 8 which projects through a slot 9 in the wall 10 of the box, this being provided to operate the catch. The member also has formed integrally therewith a coiled over portion 11 forming a hook or catch which cooperates with a part 20 of the cover hereinafter referred to.

This spring member may be held in the box in any suitable manner. In the particular construction illustrated, the front wall of the body 1 is turned over, adjacent each end, 25 to form loops 12, 13, in which the ends of the strip 7 freely ride. The strip is held in spaced relation from the bottom of the box by a pair of lugs or feet 14, 15, which rest on the bottom of the box.

30 The top of the box is formed with a latch, with which the catch or hook 11 cooperates. This latch is conveniently formed by turning in the metal of the front wall 16 of the cover to form a U-shaped member having legs 17, 35 18 and a connecting web 19. When the parts are closed the hook 11 catches under the web 19, as shown in Figure 3, and securely holds the parts in position. To open the box it is simply necessary to exert a slight inward 40 pressure on the finger-piece 8, which frees the hook from the latch.

While the invention has been shown and described in its preferred form, it will be understood that it is not to be restricted to the 45 type of box shown, nor to the exact form of spring catch member, but that certain changes and variations may be made in these parts without departing from the invention as defined in the appended claims.

50 What I claim is:

1. In a box, a body and a cover, a hinge pivotally uniting these parts, a spring catch on one of these parts and a cooperating latch on the other, said catch comprising a flat 55 strip of spring metal positioned in the box with its flat sides disposed horizontally and substantially parallel with the plane of the box, bearings on each side of the box in which the ends of the strip are freely secured, lugs 60 formed on the strip adjacent the catch to space it from the bottom of the box, and a finger piece for manipulating the catch.

2. In a box, a body and a cover, a hinge pivotally uniting these parts, a spring catch 65 on one of these parts, and a cooperating latch

on the other, said catch comprising a flat spring strip with its flat sides disposed horizontally and having an integral hook member for engaging the latch, bearings on either end of the box in which the ends of the strip have free play, lugs formed integrally with the strip and disposed adjacent the hook member to space it from the bottom of the box, and a finger piece for manipulating the strip.

In testimony whereof, I have hereunto set my hand.

JOSEPH F. MORAN.
